CAN FEED

Frank D. Chapman, Berlin, Wis.

Application February 9, 1938, Serial No. 189,490

5 Claims. (Cl. 198—22)

My present invention relates generally to improvements in mechanisms for automatically handling a succession of containers or receptacles, and relates more specifically to improvements in the construction and operation of can feeds.

In general, my present invention contemplates the provision of improved can feed mechanism for quickly and effectively transferring cans or the like, in succession, from one locality to another along a relatively irregular course.

Numerous different types of can feeds for transferring tin cans or the like from one place to another and under various conditions, have heretofore been proposed and used commercially, and while many of these prior mechanisms are relatively satisfactory for most uses, they do not adequately meet certain unusual conditions of operation. Considerable difficulty has been encountered in feeding some kinds of containers, such as relatively large gallon cans, to rotary fillers, from bins or similar can supply sources located laterally of and above these machines, with sufficient speed and accuracy to insure proper positioning of the successive cans with respect to the rapidly revolving filler heads or other mechanism. The cans are usually fed by gravity from above through chutes, and are ordinarily righted by these chutes and are subsequently delivered from the discharge ends thereof in upright position to the can hooks of the filling mechanism, with the aid of a screw or helical can feed. Because of the bulk and relatively light weight of the larger cans, and the resultant frictional resistance set up by air currents, it becomes a difficult problem to positively conduct these light and bulky containers along irregular paths and with sufficient assurance that they will be properly positioned in succession beneath the rapidly traveling commodity discharge heads of fillers or the like. The ordinary can chute and screw feed have proven quite unsatisfactory for the purpose of feeding these large cans in accurately spaced relation to each other and without damaging the containers, especially when operating at high speed.

It is therefore a more specific object of my present invention, to provide a simple, compact and highly efficient can feed especially adapted to deliver large and frail cans in rapid succession and in properly spaced relation to each other, to a receiving mechanism such as a can filling machine or washer.

Another specific object of the invention is the provision of a new and useful feed mechanism

involving the combination of a feed screw with either a can supply chute or a can feed disk, or both, in such manner that the cans are quickly and positively fed to the screw most effectively and without jamming.

A further specific object of the invention is to provide an automatically functioning can feed which is especially adapted to feed empty upright sanitary cans of various sizes, to a constantly revolving mechanism from a comparatively irregular source of supply.

Still another specific object of my present invention is the provision of a simple and durable can feeding assemblage, which is dependable in operation and which enables most effective utilization of a worm or screw feeder.

These and other specific objects and advantages of the present invention, will be apparent from the following detailed description.

A clear conception of one embodiment of the invention, and of the mode of constructing and operating can feeds built in accordance with the improvement, may be had by referring to the drawing accompanying and forming a part of this specification wherein like reference characters designate the same or similar parts in the several views.

Fig. 1 is a top view of one of the improved can feeds, showing the same associated with a fragment of a can filling machine; and

Fig. 2 is an end view of the improved can feeding assemblage, likewise showing portions of the filler.

While the invention has been shown and described herein as being specifically embodied in a can feed for receiving sanitary cans in horizontal position and for delivering the same in succession in vertical or upright position to a liquid filler, it is not the intention to thereby unnecessarily restrict the scope or utility of the improvement.

The improved can feed mechanism shown in the drawing, comprises in general a horizontal feed screw having a helical can transporting flight 4 extending around and along a cylindrical core 5 which is mounted upon a drive shaft 6 journaled in a stationary frame 7 and rotated by means of chain gearing 8; a downwardly extending laterally curved can chute 9 which is curved in a vertical plane disposed at an angle of approximately forty-five degrees relative to the vertical plane of the axis of the shaft 6; a horizontal can feed disk 10 rotatable about a vertical axis by means of the upright drive shaft 11 and chain gearing 12 coacting therewith, and

being movable beneath the outlet end 13 of the chute 9 and under the helical flight 4; and an adjustable resiliently suspended can guide rail 14 extending substantially parallel to the core 5 and shaft 6 and away from the chute end 13 toward the can filling machine above the disk 10.

The worm or screw feed comprising the flight 4 and core 5 is of relatively standard construction, and extends approximately radially with respect to the axis of the filling machine, and the screw supporting frame 7 may be firmly attached to the filler frame 15. The conventional filling machine to which the can feed has been applied, comprises generally a can support 16 secured to the frame 15 and having an upper surface in horizontal alignment with the upper surface of the disk 10; an annular series of can hooks 17 revolvable above the support 16 to transport the cans 18 in succession around the axis of the machine; a liquid or commodity supply reservoir 19 located above and being revolvable with the hooks 17, and having a series of commodity discharge heads or valves 20 co-operable with the successive cans 18; and a filled can discharge disk 21 having an annular series of can hooks 22 associated therewith.

The can supply chute 9 is formed to receive the cans 18 in horizontal position as shown in Fig. 1 and is adapted to right these cans and deliver the same in succession and in upright position, onto the peripheral portion of the revolving disk 10 and into the path of action of the flight 4, as indicated in Figs. 1 and 2. The delivery end 13 of the chute 9 is preferably directed at an oblique angle relative to the axis of the shaft 6 and substantially tangent to the can circle of the disk 10, so that the constantly revolving disk 10 will pick up the successive advancing upright cans 18 as soon as they leave the chute discharge end 13, and will positively but gently position the cans against the core 5 and in front of the helical flight 4.

The can guide rail 14 is swingably supported upon an adjustable bracket 23, by means of a pivot pin 24, and the swinging portion of this rail is resiliently urged toward the feed screw core 5 by means of a spring 25, so as to constantly urge the advancing cans 18 toward this core. The supporting bracket 23 for the rail 14 and pivot pin 24 is adjustable toward and away from the can feed screw so as to properly coat with cans 18 of different diameters, by means of cap screws 26 coating with slots in the bracket 23 and with the frame 15. A second rail or guide 27 which is swingable through a horizontal slot in and independently of the rail 14, is also swingably supported from the pivot pin 24 and has a guiding projection 28 extending over and along the periphery of the support 16. The guide 27 is resiliently urged toward the feed screw by means of a spring 29, and the projection 28 is resiliently urged toward the path of advancement of the cans 18 within the filler, by a similar spring 30.

During normal operation of the improved can feed mechanism, the can filling machine and the feed screw and disk 10 are being operated in unison, and in most cases this speed of operation is relatively high or rapid. The successive can hooks 17 are being revolved past the inner end of the flight 4, and the disk 10 is rotating at a predetermined speed in the direction of the arrow as indicated in Figs. 1 and 2. When the empty cans 18 are delivered in succession to the upper end of the chute 9, they fall by gravity

through this chute and are simultaneously righted. The righted cans are delivered in succession from the discharge end 13 of the chute 9 and are deposited upon the revolving upper surface of the disk 10. The revolution of the disk 10 assisted by the inertia of the moving cans, and by the angular disposition of the chute 9, causes the successive cans to be gently delivered against the core 5 and between this core and the guide rail 14, directly in advance of the conveyor flight 4. The flight 4 thereafter immediately becomes effective to urge the successive cans 18 in properly spaced relationship toward the filler, and as the can hooks 17 proceed, the successive cans 18 are picked up and thereafter conveyed beneath the commodity supply receptacle 19 and in proper alignment with the successive discharge valve mechanisms 20. The filled cans are ultimately delivered onto the disk 21 and into the path of travel of the final discharge hooks 22, in an obvious manner.

From the foregoing description it will be apparent that the improved can feed constituting the present invention is not only simple, compact and durable in construction, but effectively performs its function of righting the cans and of subsequently delivering the successive cans 18 in properly spaced relationship to the filler mechanism. The disposition of the chute at an angle of approximately forty-five degrees relative to the vertical plane of the shaft 6 has been found quite important, and the use of the revolving disk 10 in conjunction with the chute 9 and conveyor screw, is also important. This particular association of elements has been found to effectively feed relatively large and light cans in properly spaced relationship and without damaging the cans, even when the rate of feeding is at exceptionally high speeds. The resiliently urged guide rail 14 is also important when a revolving disk 10 is utilized, since this rail will positively maintain the cans in coaction with the core 5 and will thereby eliminate possible movement of the cans away from the conveyor screw. It has also been found that while the use of a chute and screw alone were not satisfactory for feeding large and light cans, the addition of the disk 10 to the chute and screw has produced a highly satisfactory and efficient feeding assemblage. If it is not desired to utilize the chute 9 in the combination, as where the cans are fed in horizontally, this chute may be omitted and the disk 10 alone may be utilized in conjunction with the feed screw, but the invention has been found especially advantageous in cases where the righting chute 9 is utilized. The improved can feed may obviously be associated with a filler or with any other mechanism wherein the cans must be fed in properly spaced relationship, and at high speed, and it is not the intention to limit the scope by the specific disclosure of a particular type of can filling mechanism.

It should be understood that it is not desired to limit this invention to the exact details of construction or to the precise mode of operation of the feed mechanism herein shown and described, for various modifications within the scope of the claims may occur to persons skilled in the art.

I claim:

1. In combination, a feed screw rotatable about an axis, a receptacle supporting disk revolvable in close proximity to said feed screw, and a receptacle supply chute for directing receptacles in succession directly upon said disk and directly

- toward said screw at approximately a forty-five degree angle relative to the screw axis.
2. In combination, a feed screw rotatable about a substantially horizontal axis, a disk having a substantially horizontal receptacle supporting surface movable beneath and in close proximity to said screw, and a supply chute for directing upright receptacles in succession directly upon said disk surface and directly toward said screw axis at an angle of approximately forty-five degrees relative to the screw axis.
3. In combination, a feed screw rotatable about a substantially horizontal axis, a disk having a substantially horizontal receptacle supporting surface movable beneath and in close proximity to said screw, a supply chute for directing upright receptacles in succession upon said disk surface and toward said screw axis at an acute angle, and a resiliently supported guide extending parallel to said screw axis away from said chute and spaced laterally therefrom above said disk, the delivery end of said chute being disposed in close proximity to the receiving throat formed by said screw and guide.
4. In combination, a can feed screw revolvable about a horizontal axis, a disk having a horizontal

can supporting surface movable to deliver the cans to said screw, a can supply chute directed downwardly toward said surface and toward said screw at an angle of approximately forty-five degrees relative to the screw axis, and a can guide 5 extending away from said chute above said surface and parallel to the axis of said screw, the delivery end of said chute being disposed in close proximity to the receiving throat formed by said screw and guide.

5. In combination, a can feed screw revolvable about a horizontal axis, a can feed disk revolvable about a vertical axis and having a peripheral can transporting surface movable to deliver the cans to the intake end of said screw, a can supply chute extending downwardly toward said disk and toward said screw at an angle of approximately forty-five degrees relative to the axis of revolution of said screw, and a resiliently supported can guide extending away from said chute 15 over said disk and parallel to said axis, the delivery end of said chute being disposed in close proximity to the receiving throat formed by said screw and guide.
